CIGARETTE HOLDER AND ASH RECEPTACLE

Percy L. Tiller, Richmond, Va., assignor of seventy-five
per cent to Carrie Virginia Tiller, Richmond, Va.

Application August 25, 1952, Serial No. 306,212

5 Claims. (Cl. 131—175)

The present invention relates to smoker's articles and accessories, generally classified, and has particular reference to a novel ash collector and container and a cigarette holder, which is combined therewith and either permanently or removably attached thereto.

Construed somewhat more specifically, the invention appertains to an ash receptacle and cigarette holder combined, wherein the receptacle is in the form of a tray, said tray being slidably mounted in an open ended sheath-like casing and said cigarette holder being mounted atop the casing with its outer end flush with the outer end of the casing and its inner end projecting beyond the inner end of the casing so that when the tray is slid and projected to its open position, it underlies that portion of the cigarette projecting beyond the holder, whereby to receive and collect the ashes while the cigarette is being smoked.

One improvement has to do with the aforementioned combination holder and receiver, wherein the holder is optionally usable and is detachably mounted atop the aforementioned casing, making it possible to use the holder and receiver in conjunction with each other or to detach the holder and merely employ the receiver as a pocket accessory into which ashes, burnt matches and cigarette butts may be placed, temporarily stored, and carried in one's pocket when the smoker is present in a place where conventional-type ash trays and receivers are not conveniently available to him.

Another object of the invention has to do with a novel lid feature. That is to say, a lid is slidably mounted in keyways or grooves provided therefor in the casing, said lid serving to close an extending inner end portion of the ash tray when said portion projects beyond the corresponding inner end of the casing and when the other end portion of the tray is enclosed within the confines of said casing.

Briefly summarized, the preferred embodiment of the invention is characterized by a sheath-like elongated casing open at its ends, a tray telescopically slidable in said casing, said tray being of a length greater than the length of the casing, being open along its top and closed at its respective inner and outer ends, the outer closed end abutting the corresponding end of the casing and having outstanding marginal stop flanges to limit the movement of the tray in a direction inwardly and outwardly of the casing. The stop flanges engage and come to rest against said outer end while the inner end of the tray projects beyond the corresponding inner end of the casing. A lid, which is slidable in the casing, covers the open top portion of the projecting portion of the tray, and said tray is slidable relative to said lid. The upper longitudinal edges of the side walls of the tray are provided with an elongated lid accommodating and seating notches commensurate in length with the over-all length of the lid, the longitudinal edge portions of the lid overlapping co-operating edges of said side walls and being seated in the respective notches. The inner end of the lid carries a depending follower finger engageable and cooperable with the adjacent end wall of the tray. Thus, when the tray is slid from an open ash receiving position to a closed carrying position, the inner end of the tray engages the finger, slides a portion of the lid outwardly beyond the casing and the lid thus covers the then otherwise open projecting portion of the tray, whereby the complete tray, partly enclosed in the casing and partly covered by the lid, provides a satisfactory carrying container for ashes, butts, matches and refuse.

2

Other objects, features and advantages will become more readily apparent from the following description and the accompanying sheet of drawings.

In the accompanying sheet of drawings, wherein like numerals are employed to designate like parts throughout the views:

Figure 1 is an elevational view of the combined cigarette holder and ash receiver and carrier, constructed in accordance with the invention and showing the manner of using the same, a portion of the casing being broken away and shown in section.

Figure 2 is an elevational view of the holder shown in Figure 1, and showing the tray slid from left to right with the lid and cooperating portion of the tray projecting and covered for carrying purposes;

Figure 3 is an end elevation of the holder shown in Figure 2 in a direction from left to right;

Figure 4 is a cross-section taken on the vertical line 4—4 of Figure 2 looking in the direction of the arrows;

Figure 5 is a central longitudinal sectional view taken on the line 5—5 of Figure 3 looking in the direction of the arrows;

Figure 6 is an elevational view, partly in section, showing a modified form of the invention;

Figure 7 is a view of the holder shown in Figure 6, with the tray closed and with the greater portions appearing in section; and

Figure 8 is a section taken on the vertical line 8—8 of Figure 6 looking in the direction of the arrows.

By way of introduction to the detailed description, it is to be pointed out that the term "from left to right" and similar terms, such as "inner," "outer," etc., are restricted to the position of the views illustrated in the drawings.

Attention is first directed to the form of the invention covered in Figures 1—5 inclusive.

The holder for the cigarette 10 is denoted by the numeral 12 and is of a more or less conventional type, having a tapering bit 14 at the inner or right hand end. The outer or left hand end is denoted by the numeral 16.

The receiver means comprises, as before revealed, a sheath-like casing of suitable light weight rigid material, the same being denoted by the numeral 18. It is of the cross-sectional shape shown in the lower portion of Figure 4 and comprises a flat top wall 20, a curved bottom wall 22 and spaced parallel side walls 24—24. This casing is open at its outer and inner ends and on its interior it is provided with grooves 26—26 (see Figure 4) forming keyways for the longitudinal edge portions of the projectable and retractable lid 28. The inner end of the lid is provided with an L-shaped bracket, the depending portion of which provides a lid actuating finger 30. The lid is removable by sliding the same off the right end of the holder. Suitable metal or equivalent straps are anchored at their respective ends at 32—32, said straps being loop-shaped as at 34—34 to suitably embrace and removably hold the cigarette holder 12 in position atop the top wall 20 of the casing. The straps are shaped and positioned so that the outer end 16 of the holder is normally flush with the corresponding end of the casing. The inner end 14 of the holder projects beyond the inner end of the casing.

The projectable and retractable collecting tray or receptacle is denoted by the numeral 36. It is of a length greater than the length of the casing and of a cross-section corresponding with the cross-section of the passage which extends through the casing. It is open along its top and embodies a curved bottom wall 38 and spaced parallel side walls 40—40. The closed outer end, denoted at 42 in Figures 3 and 5, has a projecting marginal flange 44 providing a stop element. This engages the outer end of the casing, as shown in Figure 2, when the tray is closed and it limits sliding of the tray in a direction from left to right relative to the casing.

When the tray is in its closed position (Figures 2 and 5), a portion of the open top is confined in the casing and is thus covered by the top wall of the casing. The protruding portion of the tray is, however, covered by the slidably lid 28. The lid is of a length commensurate with the length of the casing. The marginal edge portions of the lid overlap and rest in lengthwise accommo-

dation notches 46 provided therefor in the upper edge portions of the side walls of the tray. The notches 46 extend to the end of the right hand end of the tray and terminate at their opposite ends at 48.

The aforementioned finger 30 comes into play during the act of shifting the lid from its position within the casing to its protected tray covering position. It will be apparent, in this connection, that the finger 30 cooperates with the exterior surface of the right hand closing end 50 of the tray.

Assuming that the tray is closed as in Figure 2 and one desires to use the construction in the manner shown in Figure 1, it is necessary to forcibly slide the tray and lid, as a unit, from closed position shown in Figure 2 to the ready-to-use position shown in Figure 1. In doing so, the lid 28 slides and recedes into the casing and the left hand portion of the tray continues to move and is slid out of the casing so that the open top of the tray then underlies the cigarette to trap the ashes. When the tray is slid from left to right and, thus, closed up again, the flanges 44 engage the left hand end of the casing and effect the desired over-all closing of the parts. However, and before this occurs, the end wall 50 of the tray engages the finger 30 and now the tray and lid, as a unit, slide to the position seen in Figure 2, at which time the lid covers what would be an otherwise open top portion of the tray.

In the position of the parts illustrated in Figure 2, the ashes and other refuse are trapped and contained and may be carried about in one's pocket with requisite safety. It is repeated that the casing 18 and tray 36 may be used in conjunction with each other without the cigarette holder; or, the cigarette holder may be attached (Figures 1 to 5) and employed in combination therewith in the manner illustrated in the drawings.

It may be desirable to use moldable commercial plastics in making the device and, under these circumstances, the holder and casing are permanently joined together, as shown in the modification in Figures 6, 7 and 8. In this adaptation, the open ended casing is denoted by the numeral 52 and the holder at 54, this being integrated with the top of the casing as at 56. Otherwise, the construction and operation is the same as described and the same numerals employed in Figures 1 to 5 are employed in Figures 6, 7 and 8, except 52, 54 and 56.

It is to be noted that there is an L-shaped clip 58 fixed at the left hand end of the casing and this constitutes a stop and serves to limit the sliding movement of the lid in a direction from left to right and it also checks the movement of the tray in the same direction when the wall 50 comes into engagement therewith, whereby to thus prevent the tray 36 from being pulled out too far in respect to the casing 18.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A pocket-type ash collector and carrier comprising a sheath-like elongated casing having open ends, a tray telescopically slideable in said casing, said tray being of a length greater than the length of the casing, being open along its top and closed at its ends, the outer closed end having marginal stop flanges engageable with the outer

end of said casing, the inner end of said tray projecting beyond the inner end of said casing, and a lid covering the open top portion of the projecting portion of said tray, said lid being slidably mounted in said casing, and said tray being slideable relative to said lid.

2. The structure defined in claim 1, wherein said tray is channel-shaped in cross-section and includes a bottom and side walls, the upper edge portions of the side walls being provided with elongated notches commensurate in length with the over-all length of said lid, the longitudinal edge portions of said lid being seated on the upper edge portions of said side walls and located in said notches, the outer end of said lid having a depending finger engageable with the adjacent end wall of said tray.

3. The structure defined in claim 2, wherein the outer end of said casing is provided with a depending stop for the outer end of said lid, whereby the sliding movement of the lid in one direction is limited by way of said stop.

4. An ash receptacle comprising an elongated casing open at its ends, an ash collecting tray telescopically slideable in said casing, said tray being closed at its ends and open at its top and of a length greater than the length of the casing, and a lid covering one end portion of the open top of said tray, said lid being slidably mounted in said casing, the longitudinal edge portions of said lid resting on the upper edge portions of the side walls of the tray and being restrained from upward movement by the overlying wall portion of said casing, and said tray being slideable relative to and independently of said lid.

5. A pocket-type ash collector and carrier comprising an elongated sheath-like casing open at its ends, a tray slidably mounted in said casing, said tray being open at its top and closed at its respective ends and of a length greater than the length of said casing, the outer closed

ends of said tray having marginal outstanding stop flanges adapted to abut the adjacent end of said casing and to limit the sliding movement of the tray in one direction, the upper edge portions of the side walls of said tray being provided with lid accommodating and seating

notches, a tray covering lid slidably mounted in said casing and contacting the lower face of the top wall of the casing, said lid being of a length commensurate with the length of the casing and the longitudinal edge portions thereof being seated in said notches and overlapping the

underlying edge portions of the side walls of the tray, a depending finger carried by the inner end of said lid, the adjacent closed end wall of said tray being releasably engageable with said finger, and a stop attached to and depending at right angles from the top wall of said casing

at the outer end of the casing, said stop depending into the path of movement of said lid and the outer end of said lid being engageable with said stop to limit the sliding movement of the lid in one direction in respect to said casing, and the inner closed end of said tray being adapted to abut said stop to limit the sliding movement of said tray in one direction relative to said casing.
